UNITED STATES PATENT OFFICE.

JOHN GOOD, OF FAR ROCKAWAY, NEW YORK, ASSIGNOR TO HIMSELF, PATRICK F. O'HALE, OF BROOKLYN, NEW YORK, AND JOHN M. REINER, OF RADNOR, PENNSYLVANIA.

BALL OR COP OF TWINE OR CORD.

SPECIFICATION forming part of Letters Patent No. 731,888, dated June 23, 1903.

Application filed November 25, 1902. Serial No. 132,737. (No model.)

To all whom it may concern:

Be it known that I, JOHN GOOD, a citizen of the United States, and a resident of Far Rockaway, in the county of Queens and State 5 of New York, have invented a new and useful Ball or Cop of Twine or Cord, of which the following is a specification.

The invention relates to what are known as "balls" or "cops" in which twine or cord is 10 wound in successive courses of coils which are self-retaining in proper relation to each other without a tube or any analogous internal retaining device. It is desirable that such a ball or cop, particularly one composed of 15 what is known as "binding-twine" for use in harvesting-machines, shall contain the greatest practicable length of twine within certain dimensions. It is also desirable that it shall be capable of unwinding in the freest possible 20 manner from its inside without its courses becoming tangled or snarled.

To meet the above requirements, a ball or cop embodying my invention consists in its most approved form of a substantially cylindrical body having its ends more or less concave and composed of successive regular helical courses of twine or cord, with an external binding formed by the continuation of the same thread or cord around the said body in 25 helical courses of such obliquity to the axis of the cylindrical body as to cross over both ends of said body, and so confine the several helical courses within said body in a direction parallel with the axis thereof.

30 The invention is illustrated by the accompanying drawings, in which—

Figure 1 represents a perspective view of one of my balls or cops; Fig. 2, an axial section of the same; and Fig. 3, a side view of 40 a portion of the body of the ball or cop, illustrating the winding of said body before the application of the winding courses.

1 designates the cylindrical body, the successive helical courses 2 3 4 of which, running 45 in alternately-opposite directions, are simply wound one upon another, as illustrated in Fig. 3.

5 designates the external binding, formed by winding the helical courses 6 7 8 9, of which 50 it is composed, in the manner illustrated by Fig. 1, not only over the circumference of the body, as indicated by 6 8, but also across the

ends thereof, as indicated at 7 9. There may be any suitable number of these external courses 6 7 8 9; but there generally need be 5 only a few compared with the number of courses 2 3 4 in the body. Two or three of these external courses may be sufficient, though a larger number may be used, if desirable. Only two are shown. The end of 6 the outer coil 6 9 may be made fast in any suitable manner, as by tucking into the ball or cop, as shown at 10 in Fig. 3.

To form this ball or cop, the twine or cord is wound on any suitable spindle under the 6 direction of any suitable guide, by which it may be properly guided during the rotation of the spindle, the latter being of such slightly-tapered form as to allow the finished ball or cop to be drawn off from it. The ends of the 7 cylindrical body portion 1 are made slightly concave, as shown at 11, the degree of concavity being determined by the convexity of the end disks on the spindle, which are used during the winding of the body portion and 75 slipped back out of the way when the external binding is to be applied. The slight concavity at the ends causes the successive layers of thread to tend to compress the inner layers in the longitudinal direction of 80 the axis, and so insures the integrity of the body when the end disks or guides are removed for the purpose of winding the binding course or courses. The central portions of the concave ends of the ball also receive 85 the crossing threads of the external courses, thereby maintaining the end of the completed ball substantially flat and the consequent advantage of a materially greater length of 90 twine or cord within a prescribed space. 95

In the winding of the external courses the tension which is given to the twine or cord tends to compress the ends of the body and to produce the rounding off of the ends thereof, as shown in Figs. 1 and 2.

By the terms "twine" and "cord" as hereinabove employed I intend to include all fabrics produced by the twisting of fibers—threads and yarns, for example.

What I claim is—

1. A ball or cop consisting of a substantially cylindrical body of cord or twine having concave ends and an external binding formed by the continuation of the body cord or twine

around the said body in courses of such obliquity to the axis of the body as to cross over the ends of the said body to hold the latter against collapse.

2. A ball or cop consisting of a substantially cylindrical body composed of successive regular helical courses of twine or cord and having its ends concave, and an external binding formed by a continuation of the body cord or twine around the body in courses of such obliquity to the axis of the body as to

cross over the ends of the body to hold the latter against collapse.

In testimony that I claim the foregoing as my invention I have signed my name, in presence of two witnesses, this 22d day of November, 1902.

JOHN GOOD.

LIDA M. EGBERT.

Letters Patent No. 731,888.

It is hereby certified that the name of the first-mentioned assignee in Letters Patent No. 731,888, granted June 23, 1903, upon the application of John Good, of Far Rockaway, New York, for an improvement in "Balls or Cops of Twine or Cord," was erroneously written and printed "Patrick F. O'Hale," whereas said name should have been written and printed *Patrick F. O'Hare*; and that the said Letters Patent should be read with this correction therein that the same may conform to the record of the case in the Patent Office.

Signed and sealed this 7th day of July, A. D., 1903.

[SEAL.]

E. B. MOORE,
Acting Commissioner of Patents.
